US0D1097251S

(12) **United States Design Patent** (10) **Patent No.:** **US D1,097,251 S**
(45) **Date of Patent:** **** Oct. 7, 2025**

(54) **LAMP**

(71) Applicant: **HANGZHOU GREAT STAR INDUSTRIAL CO., LTD.**, Hangzhou (CN)

(72) Inventor: **Jingjian Li**, Hangzhou (CN)

(73) Assignee: **HANGZHOU GREAT STAR INDUSTRIAL CO., LTD.**, Hangzhou (CN)

(**) Term: **15 Years**

(21) Appl. No.: **29/908,620**

(22) Filed: **Jan. 13, 2024**

Related U.S. Application Data

(62) Division of application No. 35/516,802, filed on Mar. 3, 2023 (U.S. filing date under 35 U.S.C. 384), and having an international filing date of Mar. 3, 2023, now abandoned.

(57) **CLAIM**

The ornamental design for a lamp as shown and described.

DESCRIPTION

FIG. 1 is a front plan view of a lamp showing my new design;

FIG. 2 is a rear plan view thereof;

FIG. 3 is a left side elevational view thereof;

FIG. 4 is a top elevational view thereof;

FIG. 5 is a bottom elevational view thereof;

FIG. 6 is a right, front, top perspective view thereof;

FIG. 7 is a right, front, top perspective view of the lamp in a using state;

FIG. 8 is a right side elevational view thereof; and,

FIG. 9 is a left, rear, bottom perspective view thereof.

The broken lines in the drawings depict portions of the lamp that form no part of the claimed design.

1 Claim, 9 Drawing Sheets
